CLAIM

The ornamental design for a storage bag with a seal as shown and described.

DESCRIPTION

FIG. 1 is a top perspective view of an example of a storage bag with a seal in a closed configuration.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a top perspective view thereof in an open configuration.

The broken lines depict portions of the storage bag with a seal that form no part of the claimed design.
